PORTABLE MIXER

Gaston S. P. de Bethune, New York, N. Y.

Application June 1, 1935, Serial No. 24,561

28 Claims. (Cl. 259—96)

This invention relates to agitating apparatus, more particularly to apparatus for stirring or admixing a plurality of constituents, of which one or more is fluid, and especially to a well-known class of such mixers sometimes termed portable, being convenient for manipulation, although the present improvements are in no wise essentially limited to utilization with such mixers. Portable mixers usually comprise as elements a motor, an extended shaft coupled to the shaft of the motor either directly or through a system of gears to step up or reduce the R. P. M. and a system of single or multiple impellers assembled upon the extended shaft and adapted to operate in a container upon the constituents.

To operate the mixer, in conventional use, the impeller element is dipped into the liquid contained in a tank, to which the motor is usually clamped. When the motor is started, the impeller element produces great turbulence in the liquid, by which the several phases of this latter are commingled, but it is well known that such mixers are only adapted to the treatment of constituents easily admixed, and often the energy imparted to the liquid by the impeller element is largely dissipated in useless eddies.

Moreover under ordinary conditions that part of the shaft which extends through the liquid and is exposed directly thereto produces almost instantaneously by its rotation an air vortex along the shaft as at A—D in Fig. 17, to be hereinafter more particularly referred to. Such a vortex I call hereinafter "shaft vortex".

When the shaft stands substantially upright in the liquid, the shaft vortex, after the rotation of the motor and the conditions in the tank have established the normal regime, is sloped substantially as a surface of revolution about the axis of the shaft, whose directing curve is shown in Fig. 17 by the line A B C D. It is noteworthy that air is projected from the vortex into the liquid, and large bubbles are so projected, about the upper part A B of the curve, whereas around the lower portion C D a continuous stream of very fine bubbles leaves the shaft and is injected into the liquid.

If the shaft were long enough and the fluid not very viscous, it is probable that the curve below D would extend asymptotically to the rectilinear element of the shaft and that consequently in its lower portion the air layer of the vortex around the shaft is extremely thin; thus the air particles emitted from the vortex into the liquid are also extremely minute. Such a condition is highly detrimental in any case where the liquid

mixture treated in the tank is in the least susceptible to foaming.

The shaft vortex under certain conditions may extend down to the impeller and separate completely the liquid from the shaft, forming what I call hereinafter an "outer vortex". This happens, for example, when under the action of the impeller, the whole mass of liquid rotates with sufficient velocity around the tank so that it completely leaves the vicinity of the shaft and establishes itself in dynamic equilibrium along a paraboloidic surface of revolution under the action of centrifugal force, see line E F, Fig. 17. Such a vortex has also a very detrimental foaming action.

An important object of the invention is to provide such a mixer with means suitable to avoid the absorption of air by the liquid mixture and consequently to avoid foaming, and another object is to provide a mixer with means effective to increase its mixing efficiency.

Still another object of this invention is to construct said means in such a way that they may be easily removed from the mixer for purposes of cleaning, and may be easily reassembled.

A further important object of this invention is to assemble said means in such a way that they may easily be adapted to the various conditions of viscosity of the liquid under treatment.

In pursuance of the above general objects, a cognate object is to provide that the impeller element shall rotate inside of a casing, with a moderately close clearance, said casing being arranged to surround the system of impellers and being provided with an opening suitable for the passage of the shaft; an opening suitable for taking in the liquid; and an opening suitable for discharging said liquid, after having submitted it to an extensive mixing effect, into the bulk of the liquid within the tank, in such a way that useful eddies are created within said tank and so that substantially all parts of the liquid mass may successively be taken into the casing; also so that there be not created an outer vortex under the action of the discharge. Said casing is arranged to be supported by adequate means, according to the invention, as will be explained hereinafter, and means are provided by which it may be assembled with the motor as a unitary structure, susceptible of convenient manipulation.

I provide secondly that for that part of the shaft which is likely to contact with the liquid mixture during the operation of the mixer, the shaft shall rotate within a sleeve of suitable shape, so as to maintain within said sleeve the

shaft vortex unavoidably created by the rotation of the shaft and prevent any air being projected into the liquid, said sleeve being attached to the motor, and I provide furthermore that said sleeve can be used as means to support the casing and connect it for simultaneous assembling of the sleeve and of the casing with the motor.

I provide also that the combined sleeve and casing be formed in two parts, splitting in a diametral plane along the axis of the shaft, one or both of which parts may be attached to the motor, and said parts being assembled with each other, in order that each of them may easily be removed from the other and from the motor.

15 Other objects are to so provide that the combined sleeve and casing be formed in three parts, one of them being a frame assembled upon the motor and the two other parts being symmetrical covers assembled upon said frame, in order that 20 said covers may easily be removed from the frame, and thus afford a compact, sturdy, easily mountable and demountable unit.

Again the invention includes such an organization of the elements that the discharge orifice 25 shall be adjustable, both as regards the cross-sectional area of the discharge nozzle and the direction of the discharged stream so as to prevent the liquid mass within the tank from acquiring such centrifugal momentum as to form 30 an outer vortex.

So also, I provide that the intake opening and the discharge opening shall be arranged in such a way that the discharged products force the untreated products to move toward the intake, 35 thereby making sure that substantially no part will remain untreated outside of the mixer.

Heretofore, efforts have been made to prevent foaming, and to permit the employment of high mixing speeds by carrying out the mixing in an 40 autoclave, into which the stirring element is usually introduced by means of a stuffing box. These efforts have not proven entirely satisfactory, however, for one reason that any air which 45 may be in the autoclave will induce some foam, and consequent increase in pressure, in mixtures where such foaming is an undesirable characteristic, moreover such a mixing device is not portable; i. e. not adaptable to be easily transferred from one container into another, without disassembly and reassembly, and it cannot of course 50 be satisfactorily operated in the absence of a stuffing box.

Inasmuch as it is difficult to provide for the entire exclusion of air or other gas from an autoclave, and as mixtures treated in open containers are desirably visible for observation, another object of the invention is to provide means whereby mixing may be carried out in an open container at high speed with the resultant thorough admixture of the constituents in a final product which 60 is not characterized by a high over-run or internal tension due to occluded air or other gaseous inclusion.

In practice I have been able to admix in the 65 open, certain liquid constituents by the use of my present invention with the same degree of efficiency and speed as is possible by employing the conventional homogenizer, wherein pressures up to 5,000 lbs. per square inch are commonly employed.

70 Furthermore, I am able to run the impeller at speeds up to 10,000 R. P. M. without overflow. It is impossible to employ such high speed in any of the commercial portable mixers operating in open containers with which I am familiar, and

the use of an autoclave is undesirable in many installations for which my novel mixing apparatus is applicable.

Other objects and advantages will appear as the description of the particular physical embodiment selected to illustrate the invention progresses and the novel features of the invention will be particularly pointed out in the appended claims.

5 In describing the invention in detail and the particular physical embodiment selected to illustrate the invention, reference will be had to the accompanying drawings, and the several views thereof, wherein like characters of reference designate corresponding parts, and in which:

10 Fig. 1 is a vertical sectional view of a complete mixing apparatus with an embodiment of my invention applied thereto;

15 Fig. 2 is a view in horizontal transverse section on the line 2—2 of the device as shown in Fig. 1;

20 Fig. 3 is a fragmentary, detail view in transverse section on the horizontal plane indicated by the line 3—3 of Fig. 1, the arrows at the end of the line indicating the direction in which the view is taken;

25 Fig. 4 is a detail view of a modified form of nozzle;

30 Fig. 5 is a view similar to Fig. 1 of a modified form of mixer unit;

Fig. 6 is a similar view of another modification;

Fig. 7 is a similar view of a form of mixer in which a cylindrical sleeve is utilized;

Fig. 8 is a fragmentary detail view in vertical longitudinal section on an enlarged scale, showing a part of the shaft and sleeve of Fig. 7;

Fig. 9 is a view similar to Fig. 8 of a modification, and Figs. 10, 11 and 12 show similarly other modifications of the co-operating shaft and sleeve structure;

Fig. 16 is a similar view of a co-operating mixer casing part; and

50 Fig. 17 is a diagrammatic view illustrating the mode of propagation of a shaft vortex and an "outer vortex" in conventional mixing apparatus.

In the following description of an embodiment of the invention shown in the drawings, and various modifications thereof also disclosed herein, 55 it is to be understood that the devices shown are merely illustrative, and many expressions herein used are employed for the sake of brevity and not in a limitative sense, unless such limitations are indicated definitely.

60 For instance, it should be understood that the several appliances to which I shall hereinafter refer respectively as a "sleeve" and as a "casing" are in reality to be regarded as encasing elements of any suitable form; also that they can severally be used either independently or in combination, also that I shall hereinafter refer to the "impeller", such element being in reality any system of single or multiple propellers, or closed or open stirrers, such as for example the impellers of the 65 turbine type.

70 The following examples are first briefly characterized and will then be more fully described:

75 First.—Figs. 1 to 3 illustrate an assembly suitable for use in cases where the mixing action

must be intensive, for instance, in order to emulsify or homogenize liquids having immiscible constituents, and susceptible to foaming, in which case it is desirable that both the sleeve and the 5 casing shall be combined in an assembly. Figs. 13 to 16 will illustrate a modified form of this more completely enclosed type.

Second.—In cases where there is no inconvenience attendant upon the projection of air from 10 the shaft vortex into the liquid mixture, only the casing surrounding the system of impellers need be used, as shown in the form illustrated in Fig. 6.

Third.—In cases where the mixing is easy, but 15 there is danger of foaming, only a sleeve on the shaft need be used in order to prevent foaming, there being no necessity for increasing the efficiency of the internal system of impellers, and there being no danger of forming an outer vortex. Such an instance is illustrated in Fig. 7.

20 The simplest way of forming a sleeve suitable for the stated purpose is by using a cylindrical pipe, as 1, (see Fig. 7) concentric with the shaft 2 and spaced from the latter with cylinder-shaped clearance 3 which may be of moderate 25 cross-sectional area, but makes an important contribution to the purpose of the invention.

In the instance shown, the lower part of the 30 shaft is equipped with an impeller 1 and the upper part of the sleeve 1 is assembled with the motor M and is provided with air vents of which one is shown at 4 in Fig. 7. When the assembly is installed, having its lower mixer part dipped into liquid in a container, the liquid fills the sleeve up to its level in the container (not shown). When 35 the motor M is started, a shaft vortex will form within the sleeve 1 and if the liquid is rather viscous and the sleeve is long enough, said vortex will not extend low enough to discharge its air into the liquid below the lower end of the sleeve.

40 A cylindrical sleeve is, however, not desirably efficient with less viscous fluids because in such cases the tail of the vortex creeps lower, and finally reaching the lower end of the sleeve, discharges air into the liquid.

45 The tail of the vortex can, however, be prevented from creeping low enough by as simple a device as a groove 5 in the shaft 2 (see Fig. 8), because being deflected towards the bottom 6 of the groove, it comes in contact, substantially at right 50 angle towards the edge 7 of the groove, with liquid having a higher velocity and more energy. If the liquid is susceptible to foaming, there results from this contact some foaming, and the foam thus created by its surface tension opposes 55 the downward pressure of the vortex as well as the upward pressure of the liquid and helps to balance the one against the other. If the liquid is little or not susceptible to foam, as for example water, a similar phenomenon occurs in the production of a small amount of froth or fog.

60 Several arrangements of grooves 5, and collars 8 of the shaft are shown in Figs. 9, 10, 11, and 12, and any of these can be used either alone or in combination with corresponding ridges 9 or 65 grooves 10 in the sleeve. The groove 5, in combination with the sleeve 1, as shown in Fig. 8, is the embryonic stage of said more elaborate arrangements shown in Figs. 9 to 12, which I may characterize as forming a fluido-dynamic seal.

70 Obviously, my invention is not restricted to any particular form of such provisions but may extend to any possible combination of them.

I will now describe a complete embodiment of 75 my invention, i. e. the form shown in Figs. 1 to 3 which illustrate a portable mixer in which the

sleeve 10 forms the support of the casing designated generally by the reference character 11 and this latter being formed in two parts, 12 and 13.

The casing is split along a diametral plane of 5 the shaft, part 12 being assembled with the motor M by means of a ring base plate 14, bolts 15, and wing nuts 16, which pass through the upper flaring end 17 of the sleeve. The part 13 is connected with part 12 by means of vertical flanges 10 18, 19, bolts 20 and wing nuts 21, and at the bottom by a nipple 22 screwed onto threaded semi-circular extensions of the two parts.

The sleeve is preferably substantially conformable in shape to that of the shaft vortex, and the 15 narrow annular channel 24 at its lower portion, is connected to the inside of the casing by an intermediate, substantially torus-shaped space 25 and a constricted passage 26, in registry with a rib of the shaft. The combination of said rib 20 with the space 25 forms, in this case, the fluidodynamic seal for breaking the tail of the air vortex as hereinbefore explained.

The casing proper is shaped like one of my mixers as described in Letters Patent No. 1,727,753; 25 and application Ser. No. 645,363; and is here shown with two mixing chambers 27 and 28 provided with pyramidal baffles 29.

The impeller 1 is shown as built integrally with the shaft 30, which latter is assembled with the 30 shaft 31 of the motor M. The mixing members are shown as two flat vanes 32, 33 provided with peripheral notches 34 (see Fig. 2) formed obliquely at a certain angle—suitable to aid in advancing the liquid towards the discharge in the present 35 instance, the intake 35 being at the bottom.

The discharge is tangential as at D, and is provided with a screwed on nozzle N so as to permit changing easily the section of the orifice in accordance with the nature of the mixture under 40 treatment. This nozzle may be formed with a curved shank, as shown in Fig. 4, which illustrates separately a modified nozzle N' of that sort.

The discharge D opens in between the two mixing 45 chambers 27 and 28 so that the liquid is maintained in the cylindrical space 36 at a certain positive pressure which extends to the lower part 50 of the sleeve as previously explained. In some instances, however, depending on the nature of the liquid, this pressure may be too great and cause the liquid to be pushed right up into the sleeve, where it may be caused to foam within 55 the sleeve and overflow through the air vent, V, thereby bringing into the tank a certain amount of foam, which should be avoided.

To this end I have provided in the cylindrical space 36 another opening O communicating with the liquid in the surrounding tank T, so as to release the inside pressure at 36.

This opening O is provided with a nozzle o so as 60 to permit changing easily the section of the pressure-release opening, depending on the nature of the treated mixture.

It can be seen that for the purposes of cleaning, the part 13 can be very easily taken off the part 12, and this latter can then be easily disassembled from the motor M. Finally the rotor, including shaft 30 and vanes 32 and 33, can be disconnected from the shaft 31 of the motor. The whole 70 assembly is conveniently arranged for transportation and for manipulation, and may be easily attached to the lip L of the tank T by means of the bracket B and thumb-screw b, or by other suitable means, and it may readily be transferred 75

from one tank or container to another as operations may dictate.

The discharge nipple N' illustrated by Fig. 4 is such that it may be rotated about the stud D so that the liquid may be discharged therethrough in an upward direction, in the event that the mixture might contain a relatively light constituent, which might float at the top of the tank, or discharged in a downward direction, in the event that the mixture may include a relatively heavy constituent which might sink to the bottom of the tank.

In Fig. 5 of the drawings is illustrated an assembly embodying the invention in a modified form and which shows another unit in the designing of which special provision has been made for preventing foaming.

In this unit, which shows the shaft 37 of the propeller I assembled as at 38, and fixed by a set 20 screw s to the shaft of the motor M, the legs 39 support a funnel-like sleeve 40 shaped in its upper part 41 as the surface of a shaft vortex; then it has a cylindrical extension downward as at 40, and a reversed conical part 42. The sleeve is assembled by a spider 43 with the legs 39, to which it is secured by rivets 44.

The casing is formed of two parts 45 and 46, each having a ring-like flange, as 48, 49, inter-connecting the legs 39. Studs B and wing-nuts W 30 serve as fastening means.

There is in the lower casing part 45 an intake 50, and in the upper casing part 46 the opening 51 through which passes the shaft 37 and which opening is the discharge.

This casing part has preferably a generally conical shape, and as illustrated, may have walls of approximately ogee shape in vertical section. The narrow end 51 opens a little below the opening 52 of the sleeve, and the liquid discharged, having 40 a certain upward velocity, tends to produce in the sleeve a gentle pressure upward to balance the downward pressure of the vortex. There is shown a groove 5 in the shaft, which as already explained, tends to deflect the tail of the vortex and 45 to produce a little amount of foam inside the sleeve, and this ring of foam by its surface tension, balances the downward pressure of the vortex, and the upward pressure of the liquid. As previously explained, the combination of the 50 groove 5 with the sleeve 40 forms a fluido-dynamic seal.

The impeller I may of course be of any appropriate type; propeller, turbine, pump impeller, etc., and the casing may be provided with baffles 55 (not shown) to increase the efficiency of the mixing.

This mixer may be installed upon a tank like that in Fig. 1, by suitable means, not shown, with the casing and a part of the sleeve dipping into 60 the liquid contents of the tank.

When the motor operates the shaft 37, the impeller sucks the liquid into the casing and after having been projected against the walls of the casing it is discharged upward through 51.

It can be seen that, the liquid in the bottom of the tank being lifted and the liquid discharged having an upward velocity, it will tend to create a circulation downward along the walls of the tank, thus causing substantially all parts of the liquid in succession to be sucked into the casing at 50, stirred therein, and discharged into the tank.

Referring now more particularly to the modification of the device as shown in Fig. 6, this 75 comprises a motor M with extended shaft 53 equipped

with an impeller I, held by a screw 54 and washer 55 against a shoulder 56 near the end of the shaft 53.

Depending from the motor M are provided four legs 57 which support at their lower end, a part 58 of a casing element C of the casing, this part having a central opening 59 through which passes the shaft 53 and which opening acts as discharge for the liquid after it has been acted upon by the impeller I.

Upon the casing part 58 is assembled, by means of flanges, bolts and nuts, as at 60, the part 61 of the casing which is provided with a central intake opening 62.

This mixer may be installed upon a tank like that in Fig. 1, by suitable clamping means, not shown, with the impeller and lower portion of the shaft dipping into the liquid contents of the tank. When the motor operates the shaft 53, the impeller sucks the liquid into the casing and after having been projected against the walls of the casing it is discharged upward through 59.

It can be seen that, the liquid in the bottom of the tank being lifted, and the liquid discharged having an upward velocity, it will tend to create a circulation downward along the walls of the tank, thus causing substantially all parts of the liquid in succession to be sucked into the casing at 62, stirred therein, and discharged into the tank.

When the mixer is removed from the tank, it is easy to disassemble it by removing in succession the lower casing part, then the impeller, and finally the upper casing part 58 with the legs 57.

This mixer can also be provided with a tangential discharge, not shown, leading off the casing, this discharge co-operating with the upper discharge 59 to circulate the liquid; it produces also a revolving motion of the liquid in the tank, which must not be too rapid, in order to avoid the creation of an outer vortex.

This mixer, however, is not designed to prevent the shaft vortex, and in fact there is considerable air projected into the liquid by said vortex; if the R. P. M. is high enough, and if the length of the shaft is not too great, there is even air penetrating inside of the casing, where it is intimately dispersed into the liquid, so that this mixer could only be used with liquids in which dispersed air may be beneficial but does not cause any undesirable foam.

Another modification of the structural embodiment of the invention is illustrated in Figs. 13 to 16 of the drawings, and this modification has been designed with special reference to provision for a sturdy, compact, mixing apparatus, comprising a small number of parts which are easily assembled and may be readily demounted in part for cleaning or for inspection of the inner structure, or disassembled wholly, for repairs and/or replacements.

The general combination of the parts, in another embodiment of this feature of my invention selected for illustration, will be first pointed out, and a more detailed description will follow, to permit ready and complete understanding of the combinative and co-operative relationships of the components.

The main member of the mixer is a frame part F, adapted to be assembled with a motor M, and to receive a rotor R having a shaft part r assembled with the shaft m of the motor. This main frame part F may be secured to the base of the motor, as at 63, and it and the rotor derive their support from the motor and its shaft respectively.

In pursuance of the invention, one or more separately formed casing parts, of which two are shown, as C', C², are so designed as to be fitted to and supported by the frame part F, co-operating to form a cavity in which is enclosed the rotor, and having complementary vertical flanges 65 which are fastened together on each side of the elongated web 66 of the main frame member F by means of a clamp 67 with binding 10 screw 68 as shown in Fig. 15.

As will be seen from the foregoing, only four main parts are included in the mixer proper, viz., the main frame member F, the rotor R, and the casing members C', C², which in the instance illustrated are symmetrically disposed, one on each side of the frame member F. Clearly, however, if found convenient, one of these casing members could be made integrally with the main frame member F, in which event there would be only 20 three main parts, by which the chief objects of the invention can be properly achieved.

The main rotating part, i. e., the rotor R, comprises the shaft portion r already mentioned, which may be cylindrical, or of other suitable 25 contour, and which rotates in a funnel, or cone shaped chamber 80 constituted by the similarly shaped complementary wall portions 81, 82, of the main frame F and casing parts C', C², respectively. As these last-mentioned parts are identical in contour, only one will be described in detail, as C', (see Fig. 16) it being understood that the disclosure is similarly applicable to the casing member C², except where differences of structure are pointed out.

35 Next in order upon the rotor R comes a rib 69, or two or more such ribs, suitably spaced, as illustrated, if more than one is provided, and these ribs being of relatively small diameter, their purpose being to localize any foaming tendency which may become effective by propagation downward of the shaft-vortex which tends to develop in the funnel shaped chamber 80, this latter being of rather close conformity to the shape of a shaft-vortex. The surrounding walls 40 81 of the main frame F and the complementary wall parts 82 of the casing parts C', and C² are preferably suitable contours to provide annular recesses 70 in registry with the annular ribs or ridges 69, as such co-operation of contour has 45 been found a practical means of limiting the downward propagation of the shaft-vortex, and the upward movement of liquid.

Beyond the region just described, the rotor R 50 may have a portion of relatively smooth periphery, and of any contour suitable to promote tranquility in the chamber 71 which is shown as of cylindrical shape, and is in communication with the exterior of the mixer by means of a pressure relief vent v, (see Fig. 16). An air vent is shown 60 as at 4.

Beyond the chamber 71 are provided the mixing chambers proper of the mixer which, in the instance illustrated, comprise three such chambers 71, 72, 73 in which operate vanes 74, 65 75, and 76, having a diameter greatly in excess of their thickness, respectively, and suitably spaced apart, co-axially of the shaft to work in the aforesaid chambers, being separated by spacers 83 and 84 resembling vertebrae. Between the chamber 71, 72 and 73, extend inwardly radial wall ribs or annular shoulders 70 formed by projections 85, on the inner walls of the main frame F, and complementary substantially semi-cylindrical projections 86 and 87 75 upon the inner walls of the casing member C'

and C². The members 85 may be substantially square at their free end, and project (see Fig. 15) inward radially, beyond the adjacent ends of ribs 86, 87, so as to act as sturdy baffles.

The grooved portions or chambers 71, 72, and 73 receive the vanes 74, 75, and 76 respectively, with suitable clearance to permit progression of the liquid in a tortuous path as it advances under the influence of the inclined walls of marginal notches 88 (see Fig. 15) formed in the 10 peripheries of the vanes, the liquid finding access through a lower aperture 89, into an inlet chamber 90 below the first mixing chamber 71.

This inlet chamber 90 is desirably formed in part by a ring-shaped portion 64 formed integrally with one end of the main frame member F, for the sake of strength and for convenience in the assembly and subsequent rigidity of the complementary casing parts C', C² which are fitted in between the upper face of this ring 20 and the lower face of the substantially ring-shaped flange 63 by which the other end of the frame member F is secured to the base of the motor M. The flange parts 63 and 64 lie in substantially parallel planes, one at each end of 25 the frame part 66, which connects the flanges 63, 64 to each other, lying at right angles therebetween.

The contour of the chamber 90 may desirably be cylindrical as it is proper that the liquid 30 should enter the mixer in a relatively tranquil condition and receive its first rotary motion by contact with the end 91 of the rotor structure. This end is formed with a cap 91 screwed upon a threaded end 92 of shaft portion 93, upon 35 which are assembled co-axially the vanes and their spacers 83, 84, in the manner shown most clearly in Fig. 13, and 94 indicates a shoulder on the shaft to serve as an abutment for this series of rotor members.

The next phases of mixing are characterized 40 respectively by extreme turbulence, in pursuance of the invention as carried out in the present embodiment thereof, and to promote such turbulence the mixing bays, 71, 72, and 73 are 45 respectively formed with peripheral walls which in the casing parts C', C² are of conical section, as shown clearly in Fig. 16 at the regions indicated in the last cited reference characters.

For a description of the theory and practical 50 efficiency of turbulence so secured, reference may be had to my already mentioned Letters Patent No. 1,727,753; and for a similar disclosure of the desirability of introducing the fluid in a relatively tranquil condition, reference may be had to my co-pending application, Serial No. 645,363 but it is sufficient to state at this point that the structure shown in the drawings of my present application, with special reference now to Figs. 13 to 16 thereof, has been found in practice to give very satisfactory results.

When the motor M rotates, the impeller I 55 sucks the liquid into the casing and after having been mixed in the chambers 71, 72, and 73, whereby a very efficient mixing action is produced, it is discharged outward tangentially 65 through the nozzle 95 which may desirably be formed with rosette openings 96, to spread the discharge and prevent the formations of useless eddies.

It can be seen that the liquid in the bottom 70 of the tank being lifted, and the liquid discharged having an upward velocity, it will tend to create a circulation downward along the walls of the tank, thus causing substantially 75

all parts of the liquid in succession to be sucked into the casing. When the mixer is removed from the tank it is easy to disassemble it by removing in succession the parts C', C², and then 5 the impeller (at the same time with the rotor assembly.)

It can further be seen that, if the mixer is provided with several impeller elements such as the several vanes shown in Figs. 1 and 13, each of 10 them acting in a specially contoured chamber of the casing, when a portion of the liquid mixture is taken into the casing it is in succession submitted to the action of each impeller element, said action being at an optimum efficiency near the 15 periphery of the element, where the smashing force applied to the particles of the mixture is maximum; then in the interspace between two impeller elements, the pressure is stepped up, and consequently the energy needed to rotate the next 20 element is increased, i. e. the energy available for applying the smashing force is larger, which is a very favorable circumstance, because the particles already reduced in size by the action of an impeller element are, after a certain time, acted 25 upon with a larger smashing force so that during the passage through the mixer of a portion of the liquid mixture, said portion has been acted upon several times generally intermittently with increasing efficiency at each step. When said portion 30 is discharged from the mixer and is returned to the bulk of the liquid mixture in the tank it commingles gently with portions of the liquid mixture in a less advanced stage, thus improving their average conditions. When now a new 35 portion of said bulk is taken into the casing, it is already better than the one previously considered and its condition consequently will be more improved by the intermittent action of the impeller elements under the regime of stepped up 40 pressures.

This new portion is in turn when discharged also gently commingled with the bulk of the liquid mixture in the tank, said liquid mixture being thereby again improved in its average 45 condition.

After a certain time, depending upon the rate of discharge and the volume of the tank, the average condition of the liquid mixture will be satisfactory, although according to the laws of 50 probability, there may still be some freak unsmashed particles, their number, however, tending towards zero.

Portable mixers are used extensively in almost 55 every branch of the chemical industry and also of the food industry, as well as in many other industries, and for all such uses mixing apparatus in the construction of which my improvements have been embodied present desirable advantages of operation over known types of mixing 60 apparatus.

As examples of applications in which difficulties of operation which are well-known to those skilled in the industry have been obviated by the 65 utilization of the present improvements, two such achievements will be instanced, as follows:

Example I.—When the mechanical emulsification of tallow in soap solution has been attempted according to conventional usage, if turbulence is imparted to the solution while exposed 70 to air, an extensive foaming occurs.

Per contra, a highly satisfactory emulsion of the above character can be produced safely, and without foaming, at temperatures between 100° 75 F. and 150° F. by using a portable mixer of my

improved type, operating in an open tank as illustrated in Fig. 1.

Example II.—It is possible to reconstitute cream by emulsifying butter in milk with an appropriate mixer or colloid mill, but usually it is practically 5 impossible to avoid the dispersion into the liquid complex of some air, thereby causing extensive foaming which defeats the intended purpose.

Per contra, with mixing apparatus characterized by the improvements herein disclosed, by 10 reason of the relatively high coefficient of mixing perfection attained by the impeller in combination with the casing for example as illustrated in Fig. 1, I have produced reconstituted heavy and light creams of uniform excellence; and furthermore have accomplished this difficult emulsification without foaming, a result which is attributable to the efficiency of the sleeve in controlling the shaft-vortex. 15

The foregoing disclosure shows that the several 20 forms of improved portable mixer therein described have a common characteristic in that none of them embodies a stuffing box, whereas each of them (with the exception of the portable mixer shown in Fig. 6) embodies a fluido-dynamic 25 seal, i. e. a system of protective devices whereby the deleterious extension of the shaft vortex into the liquid complex contained in the tank is effectively negatived.

It is self evident that if a stuffing box were 30 utilized at an adequate location, between the shaft of the mixer and one of the elements encasing it, a similar result could be obtained. Every craftsman who is accustomed to stuffing boxes, knows, however, how troublesome they are, and tries to avoid them whenever possible. When the packing is too loose in a stuffing box, it does not prevent air from creeping through, and when the packing is too tight therein, there is wasted an appreciable portion of the power available on 40 the shaft of the motor. Portable mixers must be both efficient and light. If the stuffing box wastes a part of the power, the mixing efficiency is reduced, and to increase the efficiency it is necessary to increase the power of the motor, thus 45 increasing the weight of the mixer, and the expense of operation. Of two motors of the same power, the light one is the faster one. Consequently, when I employ in my portable mixers as herein described, high speed motors, the extra 50 weight of the encasing parts may be more than offset by the reduction of weight of the motor, and the mixing action is considerably improved. In fact, I have built a portable mixer having a $\frac{1}{3}$ H. P. motor, weighing about 12 lbs. and capable of 55 treating 100 gallons in a very short time, with no injection of air into the liquid complex, due to the effective protection afforded by its fluido-dynamic seal.

I claim:

1. A portable apparatus for admixing, in an open container, materials at least one of which is a liquid, comprising a motor, a shaft actuated by said motor and adapted to project downwardly into said liquid from above the liquid 65 level, an agitating impeller on said shaft, means for preventing the formation of a shaft vortex in the main body of the liquid complex, said means embodying a shaft sleeve assembled on the frame of said motor, extending downwardly 70 toward said impeller, and having an opening in direct communication with the atmosphere positioned near the motor and above the level of the liquid, said sleeve surrounding that portion of said shaft from a point above to a point 75

below the liquid level in proximity to the shaft, and a constriction between the shaft and sleeve below the liquid level of the complex, said shaft and sleeve coacting to establish in the passage therebetween a dynamic balance between the pressure energy imparted by the rotation of said shaft to the air confined in said passage and the pressure energy of the liquid confined in said passage.

2. A portable apparatus for admixing, in an open container, materials at least one of which is a liquid, comprising a motor, a shaft actuated by said motor and adapted to project downwardly into said liquid from above the liquid level, an agitating impeller on said shaft, means for maintaining the level-surface of the liquid in a state of tranquility such that no air entraining vortices will be propagated therein, said means comprising a sleeve assembled on the frame of said motor and surrounding the shaft from a point above to a point below the liquid level in proximity to the shaft, and a constriction between the shaft and sleeve below the liquid level of the complex, and said sleeve extending toward said impeller, and having an opening to the atmosphere located near said motor and above the level of the liquid, said shaft and sleeve coacting to establish in the passage therebetween a dynamic balance between the pressure energy imparted by the rotation of said shaft to the air confined therebetween and the pressure energy of the liquid confined therebetween to limit the propagation downward along said shaft toward the impeller of the shaft vortex which is set up in said passage, and a casing surrounding said impeller in part at least provided with inlet and outlet ports below said shaft sleeve.

3. A portable mixing apparatus adapted to operate in an open container of the fluid constituents to be admixed, having a motor, shaft and impeller elements actuated by said motor and adapted to dip into said fluid, and a casing element assembled on the frame of said motor and having an inlet opening and a discharge orifice therein, both disposed below the level of the fluid, said discharge orifice being co-axial with said shaft and of smaller diameter than said impeller, said casing being so disposed as to envelope with said impeller a mobile body of fluid on which the impeller acts to create turbulence and pressure.

4. An apparatus for admixing, in an open container, materials at least one of which is a liquid, comprising a motor, a shaft actuated by said motor and adapted to project downwardly into said liquid from above the liquid level, an agitating impeller on said shaft, means for preventing the formation of a shaft vortex in the main body of the liquid complex, said means embodying a sleeve open to the atmosphere above the level of the liquid, and surrounding that portion of said shaft from a point above to a point below the liquid level in such proximity to the shaft as to provide a restricted annular passage between the shaft and sleeve, said shaft and sleeve coacting to establish in said passage a dynamic balance between the pressure energy imparted by the rotation of said shaft to the air confined in said passage and the pressure energy of the liquid confined in said passage and further characterized by having both the shaft and the impeller provided in part at least with casing elements adapted to co-operate for the stated purpose, said impeller casement comprising a generally beet-shaped housing with a lower centrally

disposed intake opening, and an upper opening adapted to discharge the flow of a liquid complex upward along the shaft, and said shaft encasement being of the general shape of a flue, having a flaring intake opening disposed in the line of said upward flow, and having an upwardly and outwardly flowing upper opening surrounding the shaft in spaced relation and adapted to localize said downward shaft vortex.

5. An apparatus for admixing, in an open container, materials at least one of which is a liquid, comprising a motor, a shaft actuated by said motor and adapted to project downwardly into said liquid from above the liquid level, an agitating impeller on said shaft, means for preventing the formation of a shaft vortex in the main body of the liquid complex, said means embodying a sleeve open to the atmosphere above the level of the liquid, and surrounding that portion of said shaft from a point above to a point below the liquid level in such proximity to the shaft as to provide a restricted annular passage between the shaft and sleeve, said shaft and sleeve coacting to establish in said passage a dynamic balance between the pressure energy imparted by the rotation of said shaft to the air confined in said passage and the pressure energy of the liquid confined in said passage and further characterized by having both the shaft and the impeller provided in part at least with casing elements adapted to co-operate for the stated purpose, said impeller casement comprising a generally conical housing with a lower centrally disposed intake opening, and an upper opening adapted to discharge the flow of liquid complex upward, and said shaft encasement being of the general shape of a flue, having a flaring intake opening disposed in line with the said upward flow, and having an upwardly and outwardly flaring or funnel-shaped upper opening surrounding the shaft in spaced relation, said elements co-operating to effect a discharge of said treated liquid complex laterally at a region adjacent to the proximate ends of said casing elements.

6. An apparatus for admixing, in an open container, materials at least one of which is a liquid, comprising a motor, a shaft actuated by said motor and adapted to project downwardly into said liquid from above the liquid level, an agitating impeller on said shaft, means for preventing the formation of a shaft vortex in the main body of the liquid complex, said means embodying a sleeve open to the atmosphere above the level of the liquid, and surrounding that portion of said shaft from a point above to a point below the liquid level in such proximity to the shaft as to provide a restricted annular passage between the shaft and sleeve, said shaft and sleeve coacting to establish in said passage a dynamic balance between the pressure energy imparted by the rotation of said shaft to the air confined in said passage and the pressure energy of the liquid confined in said passage and further characterized by an impeller casing having an intake opening below said impeller element, and a tangentially disposed discharge opening in said impeller casing, adjacent to said impeller.

7. An apparatus for admixing, in an open container, materials at least one of which is a liquid, comprising a motor, a shaft actuated by said motor and adapted to project downwardly into said liquid from above the liquid level, an agitating impeller on said shaft, means for preventing the formation of a shaft vortex in the main

body of the liquid complex, said means embodying a sleeve open to the atmosphere above the level of the liquid, and surrounding that portion of said shaft from a point above to a point 5 below the liquid level in such proximity to the shaft as to provide a restricted annular passage between the shaft and sleeve, said shaft and sleeve coacting to establish in said passage a dynamic balance between the pressure energy 10 imparted by the rotation of said shaft to the air confined in said passage and the pressure energy of the liquid confined in said passage and further characterized by having an impeller casing with an intake opening below said impeller 15 element, and a tangentially disposed discharge opening from said casing into the open container, said discharge opening being provided with a nozzle opening into the liquid complex chamber and serving as means by which the direction of 20 the stream discharged into the liquid complex and the ration between the area of said stream and the rate of flow induced therein by the impeller, can be regulated.

8. An apparatus for admixing, in an open container, materials at least one of which is a liquid, 25 comprising a motor, a shaft actuated by said motor and adapted to project downwardly into said liquid from above the liquid level, an agitating impeller on said shaft, means for preventing the formation of a shaft vortex in the main body 30 of the liquid complex, said means embodying a sleeve open to the atmosphere above the level of the liquid, and surrounding that portion of said shaft from a point above to a point below 35 the liquid level in such proximity to the shaft as to provide a restricted annular passage between the shaft and sleeve, said shaft and sleeve coacting to establish in said passage a dynamic balance between the pressure energy imparted 40 by the rotation of said shaft to the air confined in said passage and the pressure energy of the liquid confined in said passage and having both the shaft and the impeller provided in part at least with casing elements adapted to cooperate 45 for the stated purpose, said casement comprising a generally conical impeller housing with said impeller mounted within a mixing chamber formed therein by a portion of said cone having relatively large diameter, said chamber having 50 a lower centrally disposed intake opening, and an upper opening adapted to discharge the flow of liquid upwardly.

9. A mixing device having a driving element provided with an impeller element, said elements 55 being of a certain contour, a casing for said elements comprising a central frame part and two lateral cover parts assembled upon said central frame part, the inner wall of the casing being of a contour designed to coact with the contour of 60 the driving and impeller elements in a manner to propagate in the constituents undergoing treatment a condition of high turbulence, that part of the casing surrounding the shaft having therein an opening to the atmosphere, and the shaft and 65 casing being so relatively constructed as to cooperate to establish a fluido-dynamic seal in the constituents entrained therebetween.

10. A mixing appliance comprising a one-part frame member formed with an end portion of 70 generally annular shape, another ring shaped end portion, and an approximately flat frame part formed integrally with said end portions, the latter being disposed in parallel planes and said connecting frame part extending in a plane at 75 right angles to said other planes, a pair of sym-

metrical casing members adapted each to be fitted against one longitudinal face of said frame part between said parallel ring portions, serving with said frame part to enclose a body cavity, and a rotor encased by said frame and casing members, 5 said rotor comprising a shaft portion equipped with an impeller element, the inner walls of said cavity being formed to coact with said impeller and shaft portions of said rotor whereby to create turbulent mixing conditions within said cavity 10 upon operation of the rotor.

11. In a mixing apparatus of the class described, a shaft provided with an impeller adapted to enter a fluid complex in an open vessel, a casing enclosing at least that portion of said shaft 15 likely to propagate a vortex, said shaft and casing having intermediate the boundaries of the enclosed region a peripheral annular offset recess adapted to create a fluido-dynamic seal which 20 serves to define the limits of vortex influence 25 created in said liquid by the shaft.

12. An appliance of the class described, comprising a motor, a contoured motor shaft, and an impeller mounted on said shaft, said appliance comprising a casing including an approximately 25 flat, longitudinally disposed, core-part having its medial portion so contoured as to coact with said contoured motor shaft, and said casing including also a pair of substantially symmetrical casing parts each adapted to be fitted against one 30 longitudinal face of said core-part and each of said casing parts being of such interior contour as to complement said core-parts, said parts co-operating when assembled to envelope the motor 35 shaft and impeller.

13. An appliance comprising the shaft, impeller and casing parts combined and co-operating as set forth in claim 12, said pair of casing parts being readily removable from said core-part and shaft, and said motor being connected operatively with said shaft and associated with said core-part both when said casing parts are assembled therewith and when they are disassembled. 40

14. An appliance comprising the shaft, impeller and casing parts combined and co-operating 45 as set forth in claim 12, said pair of casing parts being readily removable from said core-part and shaft, and said motor being connected operatively with said shaft and associated with said core-part both when said casing parts are assembled 50 therewith and when they are disassembled, and a clamping means to hold said parts together when assembled.

15. A portable mixer comprising the shaft, impeller and casing parts combined and co-operating 55 as set forth in claim 12, said pair of casing parts being readily removable from said core-part and shaft, and said motor being connected operatively with said shaft and associated with said core-part both when said casing parts are 60 assembled therewith and when they are disassembled; and a means by which said motor, shaft and core-part assembly may be secured removably as a unitary structure upon a suitable support, such as the rim of an open container. 65

16. In a mixing apparatus of the class described having a shaft, an agitating impeller thereon adapted to work in a body of liquid, and a sleeve surrounding said shaft in such manner as to provide a restricted annular passage therebetween, means for creating a fluido-dynamic seal between said shaft and the surrounding sleeve to check upward movement of the liquid confined therebetween and downward movement of the air 70 confined therebetween, said means comprising an 75

annular recess bounded by the exterior wall of the shaft and the interior wall of the sleeve, said recess being offset from said annular passage.

17. In a mixing apparatus having a shaft, an agitating impeller thereon adapted to work in a body of liquid, and a sleeve open to the atmosphere and surrounding said shaft with a restricted annular passage therebetween, said shaft and sleeve having intermediate the boundaries of said passage a peripheral annular recess, divergent from said passage, adapted to create a localized condition of foam which serves to define the limits of the shaft vortex influence set up in the fluid confined in said passage.

15 18. An apparatus for admixing, in an open container, materials of which one at least is a liquid, comprising a motor, a shaft actuated by said motor and adapted to project downwardly into the liquid complex of said materials from above its normal gravity level, an agitating impeller on said shaft below said level, and means for preventing the extension of an air vortex along said shaft into the main body of said liquid complex, said means comprising a sleeve and a fluido-seal, said sleeve being assembled on the frame of said motor, said sleeve surrounding at least a portion of said shaft from a point above to a point below said level and having an opening to the atmosphere, said fluido-seal comprising an element of said sleeve and an element of said shaft above said impeller, said elements being in such proximity as to provide a restricted annular passage therebetween, said elements coacting to establish a dynamic balance of the pressure energy imparted by the rotation of said shaft to the air confined in said sleeve substantially above said passage, against the pressure energy of the liquid confined substantially in said passage.

19. An apparatus for admixing, in an open container, materials of which one at least is a liquid, comprising a motor, a shaft actuated by said motor and adapted to project downwardly into the liquid complex of said materials from above its normal gravity level, and means for maintaining the level-surface of said complex in a state of steadiness such that no air entraining vortices will be propagated therein, said means comprising a sleeve, a fluido-seal, and a casing, both said sleeve and said casing being assembled on the frame of said motor, said sleeve surrounding at least a portion of said shaft from a point above to a point below said gravity level and having an opening to the atmosphere, said casing surrounding said impeller in part at least and being provided with inlet and outlet ports below said sleeve, said fluido-seal comprising an element of said sleeve and an element of said shaft above said impeller, said elements being in such proximity as to provide a restricted annular passage between said shaft and sleeve, said elements coacting to establish a dynamic balance of the pressure energy imparted by the rotation of said shaft to the air confined in said sleeve substantially above said passage, against the pressure energy of the liquid confined substantially in said passage.

20. An apparatus of the class described, comprising an electric motor, an extended shaft connected to the shaft of said motor, an impeller assembled on said extended shaft, and a casing assembled on the frame of said motor, surrounding said rotary elements and having a throat positioned at a region intermediate said motor and said impeller, said casing having intake and dis-

charge openings positioned on the side of said throat remote from said motor and an opening to the atmosphere adjacent said motor and intermediate said motor and said throat, and said apparatus having in the region of said throat an annular recess bounded by the interior wall of said throat and the exterior wall of said shaft.

21. An apparatus of the class described, comprising an electric motor, an extended shaft connected to the shaft of the motor, an impeller assembled on said shaft, and a casing assembled on the frame of said motor, surrounding said rotary elements and having a throat at a region intermediate said motor and said impeller, said casing having intake and discharge openings positioned at the side of said throat remote from said motor and an opening to the atmosphere positioned near said motor and intermediate said motor and said throat, said apparatus having in the region of said throat an annular recess bounded by the interior wall of said throat and the exterior wall of said shaft, the inner wall of the casing in the region facing said impeller being symmetrical about the axis of said shaft and having a surface of which the radial outer portion is of conical curvature in cross section.

22. In combination, a container and a portable mixer, said mixer comprising an electric motor, an extended shaft connected to the shaft of said motor, an impeller assembled on said shaft, a sleeve assembled on the frame of said motor, and means to mount said mixer removably upon said container, said sleeve surrounding said shaft for the greater part of its length, and having a restricted zone in the region of its free end, said apparatus having in the region of said restricted zone an annular recess bounded by the interior wall of said sleeve and the exterior wall of said shaft, and said sleeve having an opening to the atmosphere positioned near said motor.

23. In combination, a container and an apparatus as set forth in claim 21, and means to mount said apparatus removably upon said container.

24. The method of admixing intensively, in an open container, all the constituents of a liquid complex having a level-surface exposed to the atmosphere substantially over its entire area, to produce a mixture throughout which all of said constituents are present in the same predetermined proportions, without aeroform inclusions: said method consisting of inducing a flow of said constituents into a zone within said container, said zone being protected from, but in direct open communication with, the main fluid body of said constituents; subjecting that portion of the materials within said protected zone to high speed turbulence and pressure; discharging said fluid continuously from said zone into the main body of fluid in such a manner as to entrain fluid from the region of the liquid level, thereby causing at said level a steady surface-flow of fluid free from air-entraining vortices, and a distribution of the constituents in said proportions; and re-circulating the fluid until all the constituents have been admixed intensively within the zone, the main body of the mixture remaining free from aeroform inclusions.

25. A method as in claim 24 in which the intensive admixture is continued until homogenization of said entire mixture supervenes, due to the high frictional coefficient of said air-free constituents in the turbulent zone.

26. In a process involving the rotation of a

- shaft through the normal gravity level boundary surface between a liquid and the atmosphere, whereby an air vortex is created immediately below said level, the step of confining said vortex within a space open to the atmosphere and limited by said shaft, by a stationary concentrical element and by a dynamically created layer of an intermediate phase composed of air and liquid and maintained by the rotation of said shaft.
- 10 27. In a process involving the rotation of a shaft through the normal gravity level boundary surface between a liquid and the atmosphere, whereby an air vortex is created immediately below said level, said shaft having radial exten-
- 15 sions operating below said normal level, said rotating elements being substantially surrounded by a suitably shaped stationary wall open to the atmosphere, the steps of causing the liquid to circulate between a part of said wall and the corresponding part on said elements, transforming the kinetic energy of said liquid to an upward pressure energy in a restricted space within said wall, and using said pressure energy to balance the downward pressure energy of said vortex,

thereby confining said vortex within a space limited by a part of said shaft, the corresponding part of said wall, and a dynamical boundary surface between the atmosphere and the liquid.

28. The process of admixing without aeroform inclusion a fluid complex of materials, in an open container, involving the rotation of a shaft through the normal gravity level boundary surface between the liquid complex and the atmosphere, and the rotational actuation by the shaft of an agitating impeller below the surface of the liquid complex, comprising the isolation of the shaft from a point above to a point below the level of the liquid complex to controvert the formation of a shaft vortex in the main body of the liquid complex, isolating with the shaft a small portion of the liquid complex, localizing the vortex set up by the shaft in that part of the liquid complex in isolation by creating a dynamical boundary surface between the liquid complex and the atmosphere, and isolating the agitating impeller in such manner as to controvert the propagation of an outer vortex in the liquid complex.

GASTON S. P. DE BETHUNE.
